UNITED STATES PATENT OFFICE

C. W. FLIPPEN, OF LAUREL GROVE, VIRGINIA.

HYDRAULIC PRESS.

Specification of Letters Patent No. 28,167, dated May 8, 1860.

To all whom it may concern:

Be it known that I, C. W. FLIPPEN, of Laurel Grove, in the county of Pittsylvania and State of Virginia, have invented a new and useful Improvement in Hydraulic Presses; and I do hereby declare that the following is a full, clear, and exact description of the same, reference being had to the accompanying drawings, forming a part of 10 this specification, in which—

Figure 1, is a vertical central section through the machine, the tobacco being in a pressed condition. Fig. 2, a similar section, the retainer being ready for the reception of 15 tobacco.

Similar letters of reference, in each of the several figures indicate corresponding parts.

The nature of my invention consists, 1st, in combining the piston of a hydraulic or 20 tobacco press, with a disk, the bore of which is of the same diameter as the piston, and with a cylinder, the hollow space of which is of a larger diameter than the piston.

To enable others, skilled in the art, to 25 make and use my invention, I will proceed to describe its construction and operation.

The cylinders of hydraulic presses used for pressing tobacco, are very heavy and unwieldly, and on account of their size and 30 weight (which latter amounts to several tons) the borings of these cylinders is attended with many difficulties and is consequently very expensive. By making the inner diameter of the cylinder head *d*, and 35 cylinder *a*, of the hydraulic press, used in combination with my tobacco press, of a larger diameter than the piston *e*, and inserting and packing a disk *c*, underneath the cylinder head *d*, the bore of which fits the 40 piston *e*, the necessity for boring the cylinder and cylinder-head is obviated and the disk *c*, alone has got to be bored. The piston plays up and down through the disk *c*, and the packing *i*, *i*, on top and bottom of 45 the disk, and the water cannot escape from the cylinder any more than if the piston would fit the bore of the cylinder itself. In this manner, the cylinder and cylinder-head can be used in the state they are in when 50 cast without the additional labor and expense of boring.

The cylinder is cast with a cylindrical recess *z*, in its top, which receives the disk *c*, and packing *i*, *i*. The cylindrical flange *y*, 55 of the cylinder head fits loosely into the recess *z*, and serves to confine the packing *i*, *i*,

and disk *c*, while the cylinder head is screwed onto the top of the cylinder *a*, by means of strong bolts *x*.

The pipe *b*, at the bottom of the cylinder 60 *a*, leads to the hydraulic pump.

The nature of my invention consists, 2nd, in an improvement in retainers of tobacco presses, viz. combining one of the retainer bolts with a lever and swivel joint on top of 65 said bolt, for the purpose of keeping the top retainer plate suspended, or raising it when necessary.

The press frame consists of a top plate *p*, and a bottom plate *o*, upon which latter the 70 hydraulic press cylinder *a*, is placed, the two plates being connected by vertical columns *l*. The press platform *k*, has a semi-globular projection in the center of its under-surface, fitting into a corresponding 75 cavity in the top of the piston *e*, thus forming a ball joint *j*, so that there will be no strain whatever on the piston moving up and down in a vertical line, although the platform may not always be exactly horizontal. 80

The retainer consists of two plates *r*, *q*, between which the tobacco, (represented by blue lines in Fig. 1) is placed. Two vertical bolts *s*, *s*, are fastened to the bottom plate *r*, 85 of the retainer, and their screw threaded upper ends pass through smooth holes in the top-plate *q*. Nuts *t*, screw on the bolts *s*, above the top plate *q*.

The bottom plate *r*, is provided with 90 wheels *n*, which run on rails *m*, on the press platform *k*.

A lever *v*, is connected with the upper end of one of the retainer bolts *s*, by a kind of a swivel joint, the lever resting in a fork *u*, the socket of which turns freely in a hole in the upper end of the retainer bolts. Thus 95 the lever and fork can be turned to the right or left, and the lever can be worked up or down, the fork serving as its fulcrum.

The operation of the machine, is as follows: The retainer with the tobacco piled up between the two retainer plates *q*, *r*, and the nuts *t*, at the upper ends of the bolts *s*, (as represented by black lines in Fig. 1) is 105 placed upon the rails of the press platform *k*, while the platform *k*, and piston *e*, are in the position represented by red lines in Fig. 1. The lever *v*, is turned sidewise as represented in Fig. 1, so as to be out of the way. 110 The hydraulic press is then worked so as to raise the press piston and press platform *k*,

and also the lower retainer plate r , and press the tobacco between the latter and the top retainer plate q , which rests against the top plate p , of the press frame. While the pressing operation proceeds, the bolts s , pass up through the holes in the top retainer plate q .

When the tobacco has been sufficiently pressed, the nuts t , are screwed down (as indicated by red lines in Fig. 1) so as to 10 keep the retainer plates together and the tobacco in a pressed condition, while the press piston, press platform and retainer are made to descend to their original position. The retainer is then run out on the rails m , as 15 represented at t' , q' , s' , r' , in Fig. 1. The nuts t' , are then screwed up to the top of the bolts s , the lever v , is turned around and its inner end inserted in hook w , attached to the center of the top retainer plate q , (all as 20 represented in Fig. 2) and the plate q , is lifted up by depressing the outer end of lever v , and kept in this position until the pressed tobacco has been removed and a new pile of tobacco placed upon retainer 25 plate r . The outer end of lever v , is then raised so as to allow the upper retainer plate to descend until it rests on top of the pile of tobacco, when the retainer is run back upon the rails of the press platform and the 30 pressing operation repeated, as above described.

The employment of the lever v , is of great advantage because the upper retainer plate can at once be lifted from the pressed tobacco or be dropped on the new pile of tobacco as heretofore set forth, without the labor and loss of time consequent upon the use of two nuts for each retainer bolt, one

nut t , above and another one below the upper retainer plate. Such a nut below the 40 plate q , must be screwed up after the tobacco has been pressed and the retainer been run out, in order to raise the plate q , and keep it in a raised position until the new pile of tobacco has been inserted. The nut must 45 there be screwed down in order to allow the plate q , to descend until it comes to rest on the pile of tobacco. As the heavy plate q , rests upon such a nut while being screwed down, this cannot be done except by using 50 a wrench, an operation which causes a considerable loss of time and labor.

By dispensing with the use of nuts below the upper retainer plate q , and employing a swivel jointed lever v , as above described, the plate q , can be dropped in an instant.

What I claim as my invention and desire to secure by Letters Patent is—

1. Combining the piston of a hydraulic or 60 tobacco press, with a disk the bore of which is of the same diameter as the piston and with a cylinder, the hollow space of which is of a larger diameter than the piston, substantially as and for the purposes set 65 forth.

2. In the retainers of tobacco presses, combining one of the retainer bolts with a lever and swivel joint on top of said bolt, for the purpose of keeping the top retainer 70 plate suspended, or raising it when necessary, substantially as set forth.

CHARLES W. FLIPPEN.
